(57) CLAIM

The ornamental design for a collapsible crab trap, as shown and described.

DESCRIPTION

FIG. 1 is a perspective view of the collapsible crab trap in closed condition, showing my new design;

FIG. 2 is a view similar to FIG. 1 showing the trap in open condition;

FIG. 3 is a right side elevational view thereof;

FIG. 4 is a top plan view of the trap in partially assembled condition; and,

FIG. 5 is a perspective view of the trap in condition for transport.
